Michael Woffer
Lettors Patent

6174X

The subscriber refers to in these Letters Patent and making part of the same containing a description in the words of the said Michael Woffer himself of his improvement in cleaning all kinds of grain from their chaff, ears, dust, &c.

To all to whom these presents shall come. Be it known that I, Michael Woffer of Upper Milford Township in the County of Lehigh & State of Pennsylvania have invented a new & useful improvement in the machine for cleaning all kinds of grain from their chaff, dust, ears &c. & that the following is a full & exact description of the construction & operation of the said machine as invented or improved by me.

This machine or instrument is intended to be a very useful implement to the farmer, rural economist & dealer in grain by enabling him to separate the grain from their chaff, dust, ears &c. by an operation much easier than by any other known method as he believes now in existence in use, at any rate he offers it as containing a new & useful mode of effecting the purpose for which it is constructed. The description of his invention & discovery, is contained in the following words & terms that is to say. He forms a frame of suitable scavelling, 5 or 6 feet long one foot 5 inches wide with a depth or height about 4 feet with 5 pediments legs, 12 feet 5 or 6 inches high is formed to a box with suitable boards like the old fashioned wind mill. Within the box there is a shaft with 4 pins outside there is a small cogged wheel of about 16 cogs & fastened to the said shaft, above this is a large wheel with 45 cogs, & at this is a hand wheel outside of the box runs another shaft & at this is likewise a cogged wheel with 12 cogs at the end & a pulley about in the middle of the machine said shaft may be fastened to the legs in any other way, inside there is another shaft of about 2 feet sometimes longer & each on 2 cog wheels at this is likewise a pulley at the one end so as to correspond with the middle shaft pulley, & may be secured at said shaft to a seat with screws

Patent of 1/4 inch thick & of the said arms are flat as long as the sieve, the same is about 14 inches long & about 14 1/4 wide in diameter & is applied about 8 inches of said like arms. Below this shaft is a semicylinder of iron 10 inches long & open at one end & wide enough to admit the concave wheel to run without hindrance, at the hinder part a hole is left for the concave wheel on each side one so as to bring the sieve below and above level, on the top there is a hopper wide enough to miss the semicylinder, below the sieve there are likewise 2 boards running nearly from one end to another the top to the other end. Now by setting the largest cogged wheel in motion by human or any other strength or power, it turns the said shaft inside & the other outside of the hopper & from turning the outside shaft the inside or sieve & said shaft is turned by a trap or cogged wheel, then the concave, & also the sieve is in motion so as by turning the largest cogged wheel about 3/4 round the sieve & concave turn once. The concave is in the semicylinder & by throwing grains in the hopper it falls down in said cylinder, from where the concave works it out into the sieve where the kernels fall thro & glide along the slant board & the dust shaft & fall out behind as in the common way. The peculiar & special merit of this invention discovery & improvement is this to wit. the revolving sieve so as by turning, it makes its regular revolution, also the semicylinder where the concave makes its revolution by which the work is rendered much better & easier & that the said ^{inventor} to secure by ^{obtaining} Patent to the end that he may enjoy the exclusive benefit thereof & also the reel & inside shaft as well as the sieve so as to bring the sieve under & above level. That he begs also to enjoin me his Patent to the purpose of condensing his invention & improvement as pre- said more perfectly plain & intelligible be forwarded with these presents to the Secretary of State for safe keeping in the Patent Office a model exhibiting the whole of his machine as related to its principal parts & manner of acting & of the several parts, containing with the description of the same done by the said Michael Thompson for the time of application at office of Mississ. Township in the County of Kings.
